UNITED STATES PATENT OFFICE.

MELVILLE E. PETERS, GEORGE H. FATH, AND ALBERT F. MILLER, OF DENVER, COLORADO, ASSIGNEES TO THE PETERS PATENT RIGHTS COMPANY, OF DENVER, COLORADO, A CORPORATION OF COLORADO.

FIRST-STAGE TREATMENT FOR BOX-WRAPPING MACHINES.

1,251,813.

Specification of Letters Patent.

Patented Jan. 1, 1918.

Original application filed November 5, 1915, Serial No. 59,860. Divided and this application filed September 25, 1916. Serial No. 122,054.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful First-Stage Treatment for Box-Wrapping Machines, of which the following is a specification.

10 Our invention relates to improvements in first stage box and blank uniting and partially wrapping mechanism for box wrapping machines; and the objects of our invention are:

15 First, to provide means for receiving and positioning gummed blanks and pasteboard box shells on vertically reciprocating plungers, in such operative relation to each other as will enable said plungers to so manipulate 20 the box and blank that the bottom of each box will be glued to gummed surface of each coöperating blank.

Second, to provide means whereby said plunger coöperates with non-vertically moving side and corner wiper mechanism to wrap each blank against the opposite sides and corners of its coöperating box. And 25

Third, to provide a first stage box and blank uniting and partially wrapping box 30 wrapping machine in which automatic means is provided for wrapping the bottom, sides, corners and ends of boxes with printed or unprinted blanks or labels, and for discharging them from the wrapping mechanism, the box and blank operating mechanism being especially adapted to produce a machine that will partially wrap a larger 35 number of boxes per minute than those at present in use.

40 Our present invention relates to mechanism for partially wrapping gummed blanks around a box and appertains to the coöperative actions of two variable stroke vertically alined and movable plungers that carry 45 the blank and box down through non-vertically movable side wipers that are provided with a coöperating resiliently yielding and cushioning pressure lateral movement.

Consequently our present invention effects only the partial wrapping of a box by and 50 with a gummed blank. The mechanism of our present invention can be seen coöperatively combined in a complete box wrapping machine that forms the subject-matter of our pending application Serial No. 55 59,860 filed November 5, 1915, and our present application is a divisional part thereof.

We consequently attain these objects by the mechanism illustrated in the accompanying drawings, in which:

Figure 1, is a side elevation of a portion of a box wrapping machine, illustrating the first stage treatment mechanism.

Fig. 2, is an end elevation of the table portion of the machine, showing the side 65 wipers, the end turn-in blades and mechanism by which these parts are operated.

Fig. 3, is a vertical, longitudinal sectional view of the portion of the machine shown in Fig. 1, illustrating the relative positions of 70 the side and end wipers, and their connection with the main driving shaft.

Fig. 4, is a plan view of one of the side wipers and the coöperating corner turning blades, together with their operating mechanism and supporting standard.

Fig. 5, is a central vertical sectional view of the mechanism illustrated in Fig. 4.

Fig. 6, is a side elevation partly in section of one of the side wiper slidable supports.

Fig. 7, is a side view of the device carried by the side wiper support, and which is used in connection with extension bottom boxes.

Fig. 8, is an end view of Fig. 6.

Fig. 9, is a plan view of a portion of the 85 bed plate of the machine—showing more particularly the cam operated levers which are employed in operating the side wipers in wrapping ordinary boxes or those having an extension bottom, together with the shifting lever for locking the required cam operated lever to a rock shaft.

Fig. 10, is a front view of the supporting and operating mechanism for the upper plunger or box form.

Fig. 11, is a side elevation of part of the

mechanism shown in Fig. 10, the box form being broken away to show the box stripper. And

Fig. 12, is a horizontal sectional view, enlarged, showing the upper plunger bar and its slideway, the box stripper rod, and the latch for locking the stripper bar to the slideway head block.

Similar letters of reference refer to similar parts throughout the several views.

Referring to the drawings,—

The numeral 1 designates a supporting frame, which preferably is of box shape, but which if desired may be of any other practical shape. The supporting frame however as illustrated consists of a base plate 2, opposite side plates 3 projecting upward from the base plate, and a top flat table portion 4.

Through the center of the table portion 4 of the machine, an aperture is formed, in which a vertical plunger bar 5 is reciprocally mounted in adjustable slideway bearings 6 that are attached to the upper side of the table portion 4 of the frame. The lower end of this bar is connected to the upper end of a cam fork 7, the lower end of which engages a cam disk 8 that is secured on the main driving shaft 9 of the machine. The upper end of the plunger bar is provided with a flange 10 that is secured to a block 11 of wood or other suitable material that is made of the size and width of the bottoms of the particular sizes of box that are to be pressed against it. The top surface of this block is covered by a cushion of leather 12 or other suitable material, against which the bottoms of the boxes rest.

Our plunger and side and corner mechanism will partially cover or wrap boxes of from about 3 inches long by 1 inch wide by $\frac{1}{2}$ inch deep, up to boxes of about 14 inches long by 8 inches wide by 3 inches deep, but each different size of box must have a plunger block 11 that will fit its outside bottom length and width dimensions, as each blank rests centrally on top of this block and each box is fed to rest centrally on the blank and to rest also centrally on the top of the block, which forms a movable support for the blanks and the boxes.

Above this lower plunger block and in vertical axial alinement with it, an upper plunger bar 13 is reciprocally mounted in suitable slideway bearings 14 that are formed in an overhanging bracket arm 15 which is secured to the box frame of the machine. The lower end of this plunger bar is provided with a block 16 which we term a box form, as it is made enough smaller than the box and the block 11 of the lower plunger to fit snugly inside of the boxes.

The boxes are fed automatically centrally over the top of the blanks and in that position the upper plunger's box form descends

directly into the box against its bottom and presses the bottom of the box down tight against the blank and against the top of the lower plunger block. The lower plunger with its block reciprocates vertically a short distance and the position in which the lower plunger block first receives the blank and the box shell is the highest point or center of its vertical reciprocal movement. Consequently when the upper plunger form descends into the box against its bottom, it instantly presses it and the blank against the block of the lower plunger, which forms an abutment to the pressure of the form of the upper plunger of sufficient resistance to glue the bottom of the box to the gummed surface of the blank upon which the box rests.

The lower plunger is then drawn down by its cam and is forced down between the side wipers 17, and as these two plungers move down together the upper plunger which is arranged to move slightly faster than the lower plunger bears and consequently crowds down against it and thus holds the bottom with a constant pressure against the top of the lower plunger, and as the lower plunger moves slower on its down stroke than the upper plunger, the upper plunger in order to yield to the slower down movement of the lower plunger, is provided with a coiled spring 18, which is mounted on a bolt 19. This bolt is provided with an eye 20 that is screwed upon the bolt. This eye 20 is loosely mounted on a stud bolt 21 which is threaded into the side of the reciprocal plunger bar 13. The opposite end of the spring provided bolt is provided with a pin 22 against which a washer 23 bears, and the spring 18 is mounted on the bolt and bears resiliently at one end against the washer and at its opposite end against the under side of one end of an eye bolt 24, that is loosely mounted on the bolt 19 and which is held under adjusted tension on the bolt by two nuts 25 which are screwed down against the eye bolt and enough farther to cause the eye bolt to compress the spring until the eye bolt and the reciprocating plunger bar are under the desired tension. The eye bolt is provided with a threaded stud portion that extends loosely through and is secured by a nut to a lug that forms the terminal end of a lever 26, the opposite end of which is pivotally secured to a yoke 27 that is formed on an arm portion 28 of a yoke-shaped frame 29 which rests on and is bolted to the top table portion of the box-shaped supporting frame of the machine.

The lever 26 is reciprocated vertically by a rod 30, one end of which is provided with a yoke lug 31 which straddles the lever and a pivotal bolt 32 is extended through both the lug 31 and the lever. The lever has an elongated slot 33 and the pin 32 carries a

roller 34 which engages the edges of the slot, as the lever is raised and lowered, the said slot permitting the vertical movement of the rod 30, as will be understood. The opposite end of this rod is connected to a lever 35, which is arranged to be engaged by a cam 36, that is formed on a disk 37 which is secured on the main driving shaft 9. This main driving shaft is positioned in the box 10 frame above the base plate and it extends along the center of the width and throughout its length and it is journaled in boxes 38, that are secured to the base plate.

The oppositely arranged side wipers 15 that turn the upper ends of the sides of the gummed blanks up against the boxes are mounted on two stationary cross head brackets 39 that are secured to the top of the table portion of the frame, and they are arranged 20 on opposite sides of the box supporting plungers 11 and 16. These side wipers preferably consist of pieces of wood, the blank engaging faces of which are covered with strips of felt 40 or other suitable material 25 which is glued or is otherwise secured to each wiper. These wipers are removably secured to projections 41 that are formed on cross heads 42 that are slidably mounted in slideways that are formed in the brackets 39. There are two of these brackets, one on each side of the upper and lower plungers, and these two plungers reciprocally carry 30 each box and blank between these side wipers. These side brackets are positioned 35 parallel with the longitudinal length of the box wrapping machine, and are secured to the top of the table portion of the frame. These brackets we term the side cross head brackets. These brackets have a central 40 standard portion and two laterally extending wing portions 43, as will be seen by reference to Figs. 1, 2, 3 and 4. They each support one side and two end wrapping mechanisms. The under side of each cross head is 45 provided with a gear toothed rack portion 44, which is engaged by a toothed segment portion 45 that is formed on one end of a rock arm 46. These rock arms are pivotally secured to the brackets 39, and their opposite ends are provided with pivotal eye 50 bolts 47, through which vertically positioned rods 48 pass loosely. A collar 49 is secured on each rod by a set screw, and an expansive 55 spring 50 is mounted on the rod between the collar and the eye bolt 47. The upper end of each rod is threaded and a collar 51 is pinned to it, which engages the eye bolt 47 on the downward movement of the rod 48. The rods 48 extend down through bosses 60 52 on the brackets 39, and through the table, and rest on the ends of a bar 53, the central portion of which is secured to a vertical plunger 54 that is reciprocally mounted in a slide way formed in a transverse bracket 55, 65 that is bolted to the sides of the frame. The

lower end of the plunger bar 54, is connected by a link 56 to one end of a lever 57, the opposite end of which is rigidly secured to a shaft 58, which is mounted in a bearing standard 59, which is bolted to the bed plate. 70 On the shaft 58 are also mounted the outer ends of lever arms 60 and 61, the inner ends of which are provided with rollers, which enter respectively cam grooves in the opposite faces 62 and 63 of a cam disk 64, mounted on the cam shaft 9. Between the arms 60 and 61 and also rigidly mounted on the shaft 58 are integrally connected short arms 65 and 66, the inner ends of which are provided with holes, which are in line with corresponding holes in the arms 60 and 61. A hand lever 67 is mounted on the hub portion of the arms 65 and 66, and its forward end is pivotally attached to a locking pin 68, which is slidably mounted in the inner ends of the short arms 65 and 66. The locking pin is of such a length that when the lever 67 is shifted in the direction of the arrow, the said pin projects through the hole in the arm 66 and into the hole in the arm 61, thus locking 80 the arms 61 and 66 together, while the arm 65 is disconnected from the arm 60. The arm 60 and its actuating cam face 62 operate in connection with boxes of the ordinary type, while the arm 61 and its actuating cam face 63 operate in connection with boxes having extension bottoms, the respective cam grooves being arranged to that end. Thus when boxes of the usual type are being covered, the arm 61 is not needed, and when extension bottom boxes are being covered the arm 60 is out of commission. Therefore, when boxes of the usual type are being covered, the short arm 65 is locked to the arm 60 by shifting lever 67, and its locking pin 100 85 90 95 105 110 115 120 125 130

68, and when the arm 60 is operated by its cam 62, a corresponding movement is imparted to the short arm 65, which is locked to the arm 60 by the pin 68, and as the arm 65 is rigidly connected to the shaft 58, the said shaft is turned thereby and the arm 57, which is also rigidly attached to the shaft 58, is rocked, and movement is thus transmitted to the plunger arm 54 through the medium of the link 56. The arm 61 will be rocked by its cam 63, but it will perform no function as it is not locked to the shaft 58. Collars 69 are secured upon the lower portions of the rods 48, and between these collars and the lower ends of the bosses 52, are interposed coiled springs 70, which act to depress the rods 48, after they have been raised and then released by the cross bar 53. The vertical movement of the rods 48 causes their collars to compress the springs 50 and raise the rock arm 46, which causes the toothed ends of the rock arms which engage the rack bar 44 of the cross head 42 to move the wiper blocks against the sides of the blank and box, and hold it there with a

resilient tension, as the rods 48 are free to move through the eye bolts 47 after the side wiper is against the box. Consequently the side wipers bear against the box with a resiliently yielding pressure.

The side wipers as above described are used for wrapping box shells in a manner known as tight wrap work. When however it is desired to wrap box-shells having extension bottoms, in the manner known as extension wrap, the following additional mechanism is added to the side wipers. The sliding block of each wiper mechanism is provided with a pair of horizontally positioned cylinders 71 that depend from it. These cylinders are provided with solid head portions at one end and have nuts 72 threaded into them at their opposite ends. Axial apertures are formed through the heads and nuts, in which stems 73 are reciprocally mounted, and expansive coiled springs 74 surround the stems. The stems are provided with shoulders in the cylinder against which washers 75 rest that receive the thrust of one end of the springs when the stems are moved back through the cylinder by mechanism that is attached to their front ends, and the springs move the stems out forwardly by their expansive tension when the stems are released from backward pressure. A nut is threaded to the outer end of each stem, by which the tension of the spring can be regulated as desired. The outer ends of each pair of stems are threaded into a clip 76, see Figs. 2, 5, and 7, that is provided with a transverse pin 77, upon which is mounted a horizontal rock plate 78, having a depending bifurcated arm 79 in which is mounted a roller 80. This roller is designed to be engaged by one end of a rock arm 81, which is pivotally secured intermediate of its ends to a support 82, which is bolted to the inner face of the bracket 39. The opposite end of the rock arm is connected to a spring 83, which is attached at its opposite end to a pin 84 projecting from the bracket 39. The plate 78 has a forwardly projecting blade 85 secured upon its upper face. The pin 77 has a surrounding coil spring 86, one end of which engages the clip 76 while its other end enters a collar on the end of the pin 77. This spring normally holds the blade and its supporting plate 78 tilted upwardly, in which position it is moved against the box and over its extension lip. As the cylinders 71 move inward with the blocks 17, the roller 80 engages the arm 81, and the plate is tilted and the blade 85 engages the blank and presses it down against the extension portion of the box, the spring 83 affording a compensating movement for the blade against the box, the blades yielding backwardly from it when the cylinders and the block 17 continue slightly farther toward

the box to complete their stroke. This arrangement allows the blade to engage the box with a resilient pressure. The roller 80 engages the rock arm 81 as the cylinder moves forward and tilts the plate and its blade downwardly against the tension of the spring 83 so that the blade exerts a downward pressure on the extension lip of the box.

We will now leave the description of the extension wrap mechanism and return to the description of the tight wrap work mechanism.

The next step treatment of wrapping the blank around the box in tight wrap work is performed by the corner wipers 87. These corner wipers are used to wrap the end portions of the sides of the blank around the corners of the box as shown in Fig. 4, just before the end wipers move into action to wrap the ends of the label against the ends of the box. There are two of these corner wipers for each end of the box, one at each corner, and they each consist of a plate 87, which is provided with lugs 88, which are pivotally secured to a block 89 by a pin 90. This pin is extended beyond the lugs and a coiled spring 91 is mounted on it, one end of which is secured to a collar 92 on the lower end of the pin and the other end of the spring is secured to the adjacent lug 88. Each block 89 is tiltingly secured to the end of a toothed rack bar 93 by a pin 94 and this block is also tiltingly secured by a pin 95 to a similar rack bar 96. The two bars 93 and 96 are mounted parallel to each other in a slideway bracket 97 that is adjustably secured in slots 98 that are formed in each end portion of the bracket 39 by bolts 99, there being two sets of these corner wipers for each side of the box. Each toothed rack bar 93 is engaged by a gear 100 that is provided with side trunnions that are mounted in bearings 101 that are formed in the sides of the slideway bracket 97. Each bracket 39 is provided with bearings 102 at its ends, in which are mounted square shafts 103 having round bushings which turn in the said bearings 102, and upon the respective shafts are slidably mounted the gear wheels 100, two gear wheels being on each shaft. The gear wheels occupy the position shown in Fig. 4, or in other words mesh with the toothed bars 93, when tight wrap boxes are passed through the machine, and for loose wrap boxes, the gears 100 are shifted to engage the toothed bars 96. The gears have short trunnions, one of which enters the opening in the adjacent side of the slideway bracket when the gear is in mesh with the toothed bar 93, while the other trunnion enters the opening in the other side of the bracket 97 when the gear is in mesh with the toothed bar 96. The slideway is formed with a central partition 130

web 104, which separates the toothed bars 93 and 96, the said web having a semi-circular recess to permit of the lateral shifting of the gear wheels 100. Upon the outer end 5 of the partition web of each slideway is secured a blade spring 105 having a curved portion, which, when the gear wheel 100 is in mesh with either of the toothed bars 93 or 96, is adapted to bear upon the adjacent 10 trunnion of the said gear wheel, and thus prevent lateral shifting of the same, as will be understood by reference to Fig. 4. Each of the square shafts 103 is rotated by a gear 106 that is mounted on its forward end and 15 which is driven by a vertically disposed toothed rack portion that is formed on a bar 107 that is slidably mounted at its upper end in slideways 108 that are formed in the adjacent ends of the cross head bracket 39. 20 The lower end of this rack bar is adjustably secured to a vertically reciprocating cross head bracket 109. The slots 110 in the lower end of the rack bar where it connects with the ends of the reciprocal cross head bracket 25 permit of vertical adjustment of the rack bar.

The reciprocating bar 93 is moved by a slight throw movement of the vertical up-stroke of the cross head 109 and the vertical 30 rack bar 107 and by its pinion 106 and the pinion 100, against the corner of the blank and the corner of the box, which throw movement is sufficient to tiltly compress the wiper against its abutment spring as the 35 wiper moves against and over the corner of the box against its adjacent edges with sufficient resilient pressure to firmly glue the corners of the blank to the corners of the box. After the corner wiper has pressed the 40 corner of the blank against the corner of the box, it is thrown back away from the box by the frictional engagement of the sliding bar 96 with its slideway, which acts to accomplish this throw movement of the wiper 45 in the following manner: The spring 91 normally holds the wiper in the position shown in Fig. 4, but the block 89 is slightly tilted on both its inward and outward movement by the frictional engagement of the tooth 50 bar not operated by the gear 100, with its slideway. In the present instance, the bar 93 is engaged by the gear and the bar is moved outward or away from the box. The pull on the bar 93 by the gear wheel will 55 cause the block to tilt outward or away from the corner of the box, owing to the consequent dragging movement of the bar 96 upon which an indirect pull is exerted. Thus when the block 89, and its wiper 87 60 start forward or toward a box, the wiper is thrown out slightly, but the initial movement of the bar 93 tilts the block 89, owing to the indirect pull on the bar 96, and consequently the wiper 87 is pressed against the 65 end of the box. The pinion thus causes the

corner wiper to tilt against the box as the wiper starts across the end corner of the box, and the bar not operated by the gear 100 causes the wiper to tilt away from the box after it has completed its corner label wrapping stroke. The reciprocating cross heads 70 109 reciprocate the rack bars 107 that rotate the pinions 106 and shaft 103 that through the medium of the gears 100 reciprocate the bars 93, which move the wipers to and from 75 and across the surface of the corner ends of the box, at all four of its corners, and leave the ends of the blank glued to the ends of the box.

Loose-wrap blanks are not provided with 80 corner flaps, but the end flaps are turned up against the ends of the box as in the manner of the tight wrap blank, a slight portion of their surfaces near their outer ends having been gummed during the gumming process, 85 by which the end flap is held against the box until it reaches the second stage position. It will thus be seen that if the corner wipers were permitted to engage the end flaps of a 90 loose-wrap blank on their inward movements, the edges of the blank would be drawn away from the corners of the box in such a manner as to crumple and thereby spoil the said end flap. To obviate this action when performing loose wrap work, the pinions 100 95 on the shafts 103, are shifted to engage the rack bars 96, so that when the rack bars 93 and 96 are moved inward, a direct push is exerted on the rack bars 96, while the rack bars 93 drag in their slideway owing to the 100 indirect push exerted upon them. This action tilts the blocks 89, which throws the wipers 87 out and away from the ends of the box and maintains them thus during their inward movement. But the instant the reverse or outward movement of the wipers commences, the direct pull on the rack bars 96, and the consequent dragging of the bars 93 causes the blocks 89 to be tilted in the opposite direction, by which the wipers 87 are 105 caused to engage the end flaps and bear resiliently upon them while the said wipers move outward to the corners of the box. The flaps are thus drawn upon in opposite directions from their vertical centers outward, and the crumpling action thus prevented.

The next step treatment and the final one of wrapping the blank around the box is given by the end wipers which act simultaneously against the opposite ends of the blank and wrap them up against and glue them to the opposite ends of the box.

The end wipers 111 are designed to engage the central portions of the ends of the blanks and wipingly press them up against the ends of the box shell, and as they do this they fold and press the ends of the blanks over the corners of the blank, which have just been glued to the corners of the 115 120 125 130

box shell by the corner wipers. The box shell is carried down between the side and corner wipers, but the end wipers move upward against and over the ends of the opposite ends of the box shell. These end wipers each consist preferably of a piece of wood 111, the upper edge of which is rounded back to enable it to move smoothly against the blank. Each of these wooden end wipers has its blank engaging face covered with a strip of felt 112 and each wiper is clamped to a step of a sliding block 113 by a cap 114 and a bolt 115. The sliding block 113 is slidably mounted in a T slot 15 that is formed in the top of a head block 116 that is pivotally secured by two pins 117 to one of the ends of two reciprocating bars 118 and 119. Each of these bars is reciprocally mounted in slideways formed in 20 a bracket 120 which is adjustably mounted upon a slotted plate 121 by a bolt 122. This slotted plate 121 is slidably mounted in the table top 4. The vertical rack bar 118 of each end wiper is reciprocated as follows. 25 A pinion 123 is provided with trunnions which are rotatively mounted in bearings 124 formed in the brackets 120, and a square shaft 125 is extended loosely through the pinions of both brackets. This shaft is provided at its outer end with a pinion 126 that meshes with a rack bar 127 which is slidably mounted in bearings 128 and 129 that are formed on a bracket 130, which is secured to the end of the table. The lower end 35 of this rack bar 127 is connected to one end of a reach rod 131, the opposite end of which is connected to the upper end of a forked lever 132, the opposite forked end of which straddles the main shaft. This 40 lever is provided with a roller 133, that engages a cam 134 which imparts a reciprocal movement to said rack bar, and rotates the pinion 126 which turns the square shaft 125 and the pinions 123 that raise the rack bars 45 118 which tilt the head blocks 116 on their pins and cause their wipers 111 to tilt against the adjacent end of the blank and box, the instant the rack bars 118 are started upwardly by the pinions 123. Each tilting 50 block tilts on the pin 117 toward the box, which throws the wiper 111 against the box and the tilting of the head block is accomplished by the dragging action of the bar 119, which is held in its slideway by a friction 55 pressure which may be applied to it in any suitable manner but which I preferably create by a friction button 135 which is mounted loosely in the bracket and is held by a spring 136 against the said bar 119 60 with sufficient adjustable pressure to cause the bar to fit tight enough to hold the tilting block down in its tilted position. The pinions as they are rotated by the square shaft raise the rack bars and cause the 65 wipers 111 to rubbingly bear against the end

of the blank and box and to move upwardly across its adjacent ends to its top edge, and thus firmly glue the blank to the box over the top of the corners of the blank that were just an instant before glued to the corners 70 of the box. The end wipers bear against the ends of the box with a resiliently yielding pressure, which is imparted to each of them by an expansive spring 137 which is mounted on a pin 138 that is extended loosely 75 through an arm 139 formed on the head block 116, and is threaded into the sliding block 113. The forward throw stroke of the head block 116 is greater than that necessary to move the wiper against the box so that the block 113 slides on the head block 116 after the wiper has been moved against the end of the box. Consequently the wiper blocks 111 press the ends of the blanks with a yielding pressure against the opposite ends 80 of the box. The instant the wipers have moved up over the ends of the box, the cam 134 reverses the movement of the rack bar 127 and the direction of the rotary movement of the pinion 123, causing the rack 85 bars 118 to move downward and at the instant they start down they pull down on the pins 117, which cause the head blocks to tilt on their pins of the bars 119 and this tilting movement of the blocks on their pins 90 causes the wipers 111 to move far enough away from the ends of the box to entirely leave the same for about a sixteenth of an inch, and the friction bars 119 hold the tilting blocks in that position as they bear with 95 a friction fit in their slideways tight enough to cause the rack bars to have to pull down on the head blocks with a sufficient pressure to hold the blocks in their thrown back position away from the end of the box. 100

The end wipers are adapted to effect extension lip wrap work by means of a spring 140 which is housed in a cup 141, which is bolted to the bracket 130. A rod 142 extends through this cup and its lower end 110 is threaded and provided with nuts which strike the bottom of the cup and define the stroke of the rod. The upper end of this rod engages the under edge of an arm 143 that is secured to the side of the rack bar 127. The spring 140 is an expansive tension 115 spring and its lower end rests against the bottom of the cup 141 while its upper end bears against a cap 144 that is slidably mounted in the cup and is secured to the 120 rod 142.

The arrangement of the rack bar 127 with respect to the reach bar 131, as shown in Figs. 1, and 3, is for wrapping ordinary boxes or such as are not provided with extension bottoms. The rack bar 127 is provided at its lower portion with a slot 145 and a block 146 is bolted to the upper end of the bar 131, and is provided with a recess 125 in which rests the lower end of the rack bar 130

127, and the bar is held within the recess by a cap 147. A pin 148 passes through the lower end of the rack bar 127 and bears against the lower end of the block 146, and an adjustable block 149 bears against the upper end of the block 146, and is secured to the rack bar by a bolt 150 which passes through the slot 145. Thus arranged, the cam fork 132, the reach bar 131 and the rack bar 127 move in unison as will be understood, and with these parts thus arranged, as shown by Fig. 3, the end wipers are raised high enough to accomplish the end wiping of boxes of the greatest depth for which the machine is set. In wrapping boxes of less depth, however, the rack bar 127 must have a shorter stroke in order to diminish the rotative travel of the gear wheels 128, and to accomplish this, the adjustable block 149 is moved up a suitable distance above the block 146, and is firmly clamped to the rack bar by its bolt 150. Thus the movement of the cam 134 will raise the reach bar a short distance before the block 146 engages the block 149, after which the rack bar and reach bar move up in unison. It is necessary however that the rack bar should start to move upward simultaneously with the reach bar and move far enough to raise the end wipers 111 from the positions shown in Fig. 3, to a position where their under sides are on a plane with the upper face of the lower plunger; and this is accomplished by the spring 140, which lifts the rod 142, the upper end of which engages and exerts an upward pressure against the projection 143, on the rack bar 127, by which the pin 148 in the lower end of the rack bar is held in engagement with the block 146 of the reach bar, and the rack bar, through the action of the spring 140, moves up with the reach bar, until the nuts 151 on the end of the rod 142, engage the bottom of the housing 141, and the further action of the spring is thereby checked. After a momentary pause, during which when extension bottom boxes are being covered the end wipers are moved in toward and against the ends of the box, the cam again begins to raise the reach bar, and moves it until the block 146 engages the adjustable block 149, when the rack bar will then be raised far enough to complete its operation, being moved a distance corresponding to the depth of boxes passing through the machine. As the rack bar 127 descends, its projecting arm 143 engages the upper end of the rod 142 in the housing 141, and the spring 140 is compressed and the rod 142 depressed to the position shown in Fig. 3.

In extension bottom box work, it is necessary that the end wipers 111 should move up until their under sides are on a level with the upper face of the box bottom, and then

move inward against the ends of the box a distance equal to the width of the extension, and this is accomplished in the following manner: The racks 118 move the blocks 116 upward until the wipers are flush with the top edges of the extension bottom, then the racks reverse and tilt the block and instantly thereafter the cam 64 operates the mechanism to be presently described, which causes wipers 111 to move inwardly over the extended edges of the box. Then rack bars 118 move upward again, tilting the wipers 111 into the corner of extended edges and upward, wiping the end of the blank against the box. The inward movement of the end wipers against the ends of the box is accomplished in the following manner:

The head blocks 120 are adjustably secured to the slotted plates 121, which have a sliding movement in the table, and each plate 121 has a depending bifurcated lug 152, at its outer end, to which one end of a link 153 is pivotally secured, and the other ends of these links are connected to levers 154 and 155, which are rigidly secured upon shafts 156 and 157 respectively, which are mounted in the sides of the table. The lever 154 is a bell crank form of lever, and its other member is connected to the upper end of a rod 158, the lower end of which has a collar 159 secured thereon; a coil spring 160 surrounds this end of the rod and bears against the collar 159, and the upper end of this spring bears against an eye bolt 161, which is secured in the end of one arm 162 of a double armed lever, the other arm 163 of which carries a roller 164, which is adapted to be engaged by a cam on the peripheral edge of the cam disk 64. The double armed lever is mounted on a stationary shaft 165, which projects from a bracket 166, that forms an integral part of the cap of the adjacent bearing standard 38. The shaft 165 extends beyond the hub of the double armed lever and upon its outer end a collar 167 is rigidly secured. A coil spring 168 is mounted on the shaft between the collar and the hub of the double armed lever, one end of said spring entering a hole in the collar while its opposite end enters a hole in the hub of the lever, the spring being under a tension that will hold the roller 164 in contact with the periphery of the disk 64. The outer ends of the shafts 156 and 157 carry respectively levers 169 and 170, the lever 169 extending upward, while the lever 170 extends downward, and the ends of these levers are connected by a rod 171.

Thus when the cam on the disk 64 passes from under roller 164, the spring 168 forces the double armed lever downward, and the rod 158 is drawn upon, and the shaft 156 is given a partial rotation by the bell crank 154, the other member of which draws on the link 153 and moves the slotted plate 121

inward. Simultaneously the lever 169 on the outer end of the shaft 156 pushes on the rod 171, and the lever 170 at its other end partially rotates the shaft 157, in an opposite direction to the shaft 156, and the lever 155 on the shaft 157, draws on its link 153 by which the other slotted plate 121 is moved inward. As the plates 121 carry the head blocks 120 which support the wipers 111, it will be readily seen that the said wipers will be moved toward each other against the ends of the box, and with a resilient contact effected by the spring 160. The eye bolt 161 on the reverse movement 15 of the lever arm 162 engages a collar 172, which is pinned to the rod 158, and thus the rod is lifted, and the outward movement of the end wipers effected.

The opposite end of the shaft 157 from 20 the lever 170 carries a stop finger 173 (see Fig. 1), which when the wipers are moved to the desired point, or in contact with the ends of the box, strikes against the end of an adjustable screw 174, which is threaded 25 to a lug on the side of the frame, and any further movement of the lever arm 162 is against the spring 160, the wipers not being affected thereby.

In boxes of the usual type, or such as have 30 not extension bottoms, the inward movement of the wipers is not required, and to prevent this inward movement of the wipers, the screw 174 is screwed down until its end engages the stop finger 173, which 35 will prevent rocking of the shaft 157, and likewise of the shaft 156. The arm 163 of the double armed lever will however be moved just the same through engagement 40 of the roller 164 with the cam disk 64, but the movement of the arm 163 will be against the spring 160 and the rod 158 will not be affected thereby.

In the character of box wrapping work 45 with blanks known as loose wrap work, the same arrangement of wipers is used as for tight wrap work, as the blank which does not contain any adhesive gum except along its outer edge portions has to be wrapped around the box just the same, and the gluing 50 of the edges of the blank to the inner edges of the box takes place in the second stage treatment portion of the machine.

The two plungers after they have held 55 the box between them until the blank has been wrapped around the bottom, sides and ends of the box, separate and the upper plunger moves rapidly upward out of the box. This upper plunger however is provided 60 with a box stripper 175 which remains in the box and holds it down against the top of the lower plunger 11 until the upper plunger moves up out of the box. This stripper comprises a blade 175 which fits in a recess formed in the under side of

the plunger 16, and it is arranged and operates to hold and release the box as follows:

To the center of the blade the lower end of a rod 176 is secured, which extends up through a slideway formed in the head block 70 14 of the arm 15, and the upper end of it is connected to one end of a coiled spring 177, the opposite end of which is connected to the upper end of the plunger bar 13. One edge of the rod 176 of the stripper is provided with a notch 178 which engages and locks to an L-shaped latch 179 that is slidably mounted on top of the head block 14 of the fixed arm 15. This latch is provided with a spring 180 that normally holds it 80 against the side of the rod with sufficient resilient pulling pressure to cause it to jump into the notch 178 of the rod when the rod is moved down with the plunger's bar 13. The spring 177 of the rod is arranged with 85 sufficient contractive tension to normally hold the stripper blade up into its recess in the bottom of the plunger. Consequently it moves down with the plunger and rests inside of the bottom of the box when the plunger moves down against the bottom of the box and presses it down against the top of the bottom plunger, and the notch 178 in the rod is so relatively positioned to the spring 95 latch that when the plunger is down tight in the box and against the top of the lower plunger it locks the rod 176 of the stripper to the stationary head of the fixed arm 15, with the lower edge of its blade resting 100 against the bottom of the box. Then when the plunger starts upward the stripper stays down in and holds the box against the lower plunger. This upward movement of the plunger and its bar stretches the spring of 105 the stripper until the stripper is released from its latch. This is accomplished by a cam 181 which is secured to the side of the plunger bar in a position to engage a roller 182 on the latch when the plunger has moved 110 out of the box, and move the latch out of the notch of the stripper's rod, which then releases the stripper and allows the contractive tension of the spring 187 which has been stretched out by the upward travel of 115 the plunger's bar to jerk the stripper up into its recess in the plunger, thus fully releasing the box from the action of the upper plunger and leaving it resting loosely on top of the lower plunger, as all of the blank wipers after wrapping the blank against its 120 sides and ends move back a short distance from it. Consequently the box wrapping action of the first stage treatment station of our box wrapping machine is completed.

The box is then engaged by a transfer 125 mechanism which strikes its outer end and pushes it off of the lower plunger and from the machine.

The operation of our blank and box assembling mechanism is as follows:

The lower plunger is moved upward a short distance and receives a gummed blank 5 from the blank supplying means with its gummed surface facing upward. A box is then fed into the machine in the path of the upper plunger, which then moves down into it and carries it against the gummed surface 10 of the blank and presses the box against it with a cushioning pressure, thereby firmly gluing the blank to the bottom of the box. The operating cams of the plungers are timed to move both plungers down together, 15 and after the plungers come together and have gripped the box and blank between them they are moved down together between the side wipers, but the upper plunger moves in such relative movement to the 20 lower as will always keep the box gripped by a cushioning pressure against the blank and the top of the lower plunger.

In this box and blank gripping relation, the plungers carry the box and blank down 25 between the side wipers to the end of their downward stroke, and the opposite sides of the blank are folded up against and wrapped and glued against the opposite sides of the box automatically by this downward stroke 30 movement of the plungers and box and blank. At the end of the downward stroke of the plungers after a brief pause in which the corner and end wipers act, the upper plunger moves upward on the upward stroke 35 of its reciprocal movement, while the lower plunger remains stationary. The stripper mechanism of the upper plunger remains down in and against the bottom of the box. Consequently as the upper plunger moves 40 upward, it leaves the box resting on top of the lower plunger, from which it is moved by a transmitting device which does not form a part of our present invention. The lower plunger then moves up and receives 45 another gummed blank and the operation is repeated.

Our invention provides a simple and reliable box and blank assembling plunger mechanism for assembling the box and blank in wrapping relation, and for starting the wrapping of the blank around the bottom, sides, corners and ends of the box, and while we have illustrated the preferred construction and arrangement of our invention 50 we do not wish to be limited to it, as many changes might be made without departing from the spirit of our invention.

Having described our invention what we claim as new and desire to secure by Letters 55 Patent, is:

1. In a first stage wrapping machine, the combination with the table frame and the blank and box supporting plungers, of side wipers comprising wiper block supporting

brackets provided with a slideway, a rack 65 bar plate slidably mounted in said slideway, a blank wiping block secured in said plate in operative wiper relation to said blank and box and plungers, a toothed segment 70 ended rock arm meshing with said rack bar, a reciprocating rod secured to the free end of said rock arm by a resiliently yielding pivotal connection, and means including a cam for reciprocating said rod.

2. In a first stage wrapping machine, the combination with a table frame and vertically reciprocating blank and box gripping and feeding plungers, of two oppositely arranged brackets secured on said table, the blank and box side wipers, a rack bar reciprocally supporting said side wipers and a segment toothed ended rock arm in mesh with said rack bar, a rod resiliently connected to said rock arm and arranged to permit said side wipers to engage the sides of the blank and box with a resilient cushioning pressure, and means including a cam operated lever connected to said rock arm for reciprocating said rod.

3. In a first stage wrapping machine, the combination with a table, vertically reciprocating blank and box gripping and feeding plungers, side wipers supporting brackets on said table and a blank and box side wiping mechanism, of supports on said brackets, blank corner wipers yieldingly mounted on said arms and means including gearing for reciprocally moving said corner wipers to move against the corner end portions of said blank and box.

4. In a first stage box wrapping machine, the combination with a frame and vertically reciprocating box and blank supporting plungers, of end wipers comprising suitable blocks, slide blocks for supporting said wiper blocks, and head blocks for supporting said slide blocks, a rack bar and a smooth bar pivotally connected to each head block, power operated pinions in mesh with the said rack bars, frictional means for retarding the movements of the smooth bars in both directions of their movements, whereby the head blocks are tilted to cause the wiper blocks to engage the ends of a box, springs operating on said slide blocks which cause a yielding pressure of said wipers, said head blocks being tilted to cause the wipers to engage the ends of the box on their upward movements, and to move them out of engagement therewith, on their reverse movements.

5. In a first stage wrapping machine, the combination of the table frame, the vertically reciprocating blank and box supporting plunger with oppositely arranged blank and box end vertically reciprocating wipers comprising pressure cushioning blocks, tilting means including a positive pushing bar and a frictional dragging bar arranged to

oppose the positive pushing bar for tilting said wipers, and means including cam actuated gearing for reciprocally moving and tilting said wiper simultaneously against the 5 opposite ends of said box.

6. In a first stage wrapping machine, the combination of the table frame, and the vertically moving blank and box supporting gripping and feeding plungers, with the 10 side wipers arranged to wrap the sides of the blank against the opposite sides of the box simultaneously as said blank and box are fed down between them, means including cam controlled gearing for reciprocating 15 said side wipers against said box, with the corner wipers arranged to move to engage said blank and box at their end corners the instant said plungers have fed said blank and box to the end of its downward move- 20 ment between said side wipers, means for operatively reciprocating said corner wipers to wrap the blank against the end corners of said box, and the end wipers arranged to engage and move vertically up against the 25 opposite ends of said blank and box simultaneously and thereby wrap the ends of said blank against the ends of said box, and resilient means connected to said side and corner and end wipers whereby they engage 30 said blank and box with yielding cushioning pressures, and means including cam actuated gearing for operatively moving said end wipers.

7. In a first stage box wrapping machine, 35 the combination with a table and vertically movable box and blank receiving plungers, of oppositely positioned standards adjustably mounted on said table, side wipers slidably mounted on said standards, means for yieldingly pressing said side wipers against said box and vertically movable wipers adapted to engage the ends of the box on their upward movements, said plungers being adapted to move the box and 45 blank down between said side wipers.

8. In a first stage box wrapping machine, the combination with a table and box and blank receiving plungers, of oppositely positioned standards adjustably mounted on said 50 table, sliding members mounted on said standards, side wipers secured to said members, rocking means for sliding said members, operating means resiliently connected to said rocking means, corner wipers mounted 55 on said standards and means for imparting to them a reciprocating movement, and vertically movable wipers for engaging the box ends on their upward movements, said plungers being adapted to move said box and blank down between said side wipers.

9. In a first stage box wrapping machine, the combination with a table and box and blank receiving plungers, of standards adjustably mounted on opposite sides of said

table, rack plates slidably mounted on said standards, bell crank form of levers having toothed segments in engagement with said rack plates, push rods yieldingly connected to said levers, cam-operated means for raising said push rods, side wipers detachably connected to said rack plates, said plungers being adapted to move the box and blank down between said side wipers, and vertically movable wipers for the ends of said box.

10. In a first stage box wrapping machine, the combination with a table, oppositely positioned standards mounted thereon, laterally movable side wipers mounted on said standards, vertically movable end wipers mounted on said table, of blocks slidably mounted on said standards, corner wipers pivotally connected to said blocks, means for reciprocating said corner wipers, means for tilting said blocks to cause said corner wipers to swing inward on their forward movements and outward on their backward movements, and vertically movable plungers for receiving a box and blank and moving them down between said side wipers in position to be acted upon by the end and corner wipers, all of said wipers being adapted to engage a box with resilient pressure.

11. In a first stage box wrapping machine, 95 the combination with a table, oppositely positioned standards adjustably mounted on said table, vertically movable end wipers mounted on said table and laterally movable side wipers mounted on said standards, of rack bars mounted in pairs on said standards, a head block pivotally attached to each pair of rack bars, a corner wiper pivotally connected to each head block, a pinion in mesh with one rack bar, of each pair, and a shaft for each aligned pair of pinions, means for operating said shafts in unison, and box and blank receiving plungers for moving a box and blank down between said side wipers in position to be operated on by said end and corner wipers, all of said wipers being adapted to engage a box with resilient pressure.

12. In a first stage box wrapping machine, 100 the combination with end and side wipers, of pivotally mounted corner wipers, means for reciprocating said corner wipers, means for tilting them in one direction when moving forward, and in the opposite direction when moving backward, and forms for receiving a box and blank and passing them down between said side wipers, all of said wipers being arranged to engage said box with resilient pressure.

13. In a first stage box wrapping machine, 105 the combination with laterally movable side wipers, of forms for receiving a box and blank and moving them down between said side wipers so that the sides of said blank

will engage said wipers and be folded by them up against the sides of the box, laterally movable wipers for wrapping portions of said blank around the corners of said box 5 and means for tilting them to disengage said corner portions on their reverse movement, vertically movable wipers for engaging the end portions of said blank and folding them up against the ends of the box and over said 10 corner portions, and means for tilting them away from the box ends on their reverse

movement, all of said wipers being adapted to engage said box with resilient pressure.

In testimony whereof we affix our signatures in presence of two witnesses.
